(57) **CLAIM**

The ornamental design for a load center with integrated receptacles, as shown and described.

DESCRIPTION

FIG. 1 is a top perspective view of a load center with integrated receptacles;

FIG. 2 is an enlarged view of portion 2 shown in FIG. 1;
FIG. 3 is a front view of a load center with integrated receptacles;

FIG. 4 is a back view of a load center with integrated receptacles;

FIG. 5 is a right-side view of a load center with integrated receptacles;

FIG. 6 is an enlarged view of portion 6 shown in FIG. 5;
FIG. 7 is a left-side view of a load center with integrated receptacles;

FIG. 8 is a top view of a load center with integrated receptacles;

FIG. 9 is a bottom view of a load center with integrated receptacles;

FIG. 10 is another top perspective view of a load center with integrated receptacles illustrated in FIG. 1, shown with the door in an open position to display internal components of the load center;

FIG. 11 is another front view of a load center with integrated receptacles illustrated in FIG. 3, shown with the door in an open position to display internal components of the load center;

FIG. 12 is another back view of a load center with integrated receptacles illustrated in FIG. 4, shown with the door in an open position;

FIG. 13 is another right-side view of a load center with integrated receptacles illustrated in FIG. 5, shown with the door in an open position;

FIG. 14 is another left-side view of a load center with integrated receptacles illustrated in FIG. 7, shown with the door in an open position;

(Continued)

FIG. 15 is another top view of a load center with integrated receptacles illustrated in FIG. 8 shown with the door in an open position; and,

FIG. 16 is another bottom view of a load center with integrated receptacles illustrated in FIG. 9, shown with the door in an open position.

The broken lines in the drawings illustrate portions of the load center with integrated receptacles or environmental structures that form no part of the claimed design.
